CLAIM

The ornamental design for a flower finial, as shown.

DESCRIPTION

FIG. 1 is a perspective view of a flower finial; and
FIG. 2 is a front elevated view of the flower finial shown in
FIG. 1; and

FIG. 3 is a rear elevated view of the flower finial shown in
FIG. 1; and

FIG. 4 is a left side elevated view of the flower finial shown
in FIG. 1; the right side elevation being a mirror image
thereof; and,

FIG. 5 is a bottom elevated view of the flower finial shown
in FIG. 1.
